UNITED STATES PATENT OFFICE.

HENRY McMANUS, OF BROOKLYN, NEW YORK, ASSIGNOR TO HIMSELF,
ROBERT McMANUS, AND WILLIAM W. EASTMAN, OF SAME PLACE.

BLEACHING OIL.

SPECIFICATION forming part of Letters Patent No. 290,784, dated December 25, 1883.

Application filed March 13, 1883. (No model.)

To all whom it may concern:

Be it known that I, HENRY McMANUS, a citizen of the United States, and a resident of Brooklyn, in the county of Kings and State of New York, have invented certain new and useful Improvements in Bleaching Oil, of which the following is a specification.

My improvement has for its object to bleach or discolorize oils, removing what is ordinarily called the "bloom," and this object I effect by spreading the oil in thin films exposed to the action of air and light.

In carrying out my process I first provide an extended surface, over which the oil is caused to flow. This surface may be secured in different ways. For instance, it may consist of a series of plates carried by a large wheel which dips into a tank of oil, or it may be a thin flexible metallic band passing through a tank and upward over a pulley; but I prefer the structure shown in the drawing, consisting of parallel tubes of glass, *a*, connected to form a passage, through which heated water may be forced by a pump, *A*. A pipe, *d*, extends over the structure and is perforated, so as to conduct fine streams of oil to the upper portion of the structure and discharge them upon the tubes, over which the liquid flows to the bottom, where it is received in a suitable tank, *B*, from which it is again pumped up by a pump, *C*. By this means the oil is

spread in attenuated films over the reflecting-surfaces of the tubes, and is so exposed to the light that the requisite change is speedily effected. The bright polished condition of the tubes facilitates the bleaching of the oil, inasmuch as the light is reflected and acts with greater effect, and this is increased by heating said tubes by the flow of hot fluid through them.

I do not limit myself to the apparatus shown, nor do I claim, broadly, agitating oil or flowing it in thin films while bleaching; but

I claim—

1. The within-described mode of bleaching oil while flowing, the same consisting in exposing the oil in thin films upon bright metallic surfaces to the action of light and air, substantially as set forth.

2. The combination, in a device for bleaching oil, of a series of plates or bars presenting bright smooth surfaces, and appliances whereby the oil is discharged upon said surfaces so as to flow over the same in thin films while exposed to light and air, as set forth.

In testimony whereof I have signed my name to this specification in the presence of two subscribing witnesses.

HENRY McMANUS.
